UNITED STATES PATENT OFFICE.

CHARLES M. COLVIN, OF WILMETTE, ILLINOIS, ASSIGNOR OF ONE-HALF
TO SACKETT H. VERRALL, OF CHICAGO, ILLINOIS.

HUMIDIFYING DEVICE.

No. 839,115.

Specification of Letters Patent.

Patented Dec. 25, 1906.

Application filed May 17, 1906. Serial No. 317,297.

To all whom it may concern:

Be it known that I, CHARLES M. COLVIN, a citizen of the United States of America, and a resident of Wilmette, in the county of Cook and State of Illinois, have invented certain new and useful Improvements in Humidifying Devices, of which the following is a specification.

The main objects of this invention are to provide an improved device for impregnating the air with moisture, controlling the amount of moisture, preventing the discharge of spray from the apparatus, driving such impregnated air a comparatively long distance from the apparatus, and driving such impregnated air in any desired direction from the point at which the apparatus is located. These objects are accomplished by the device illustrated in the accompanying drawing, which represents a vertical longitudinal section of a device constructed according to this invention.

In the device shown, 1 is a cylinder open at each end and having securely mounted therein at its rear end the electric fan 2. A steam-pipe 3 extends into the cylinder 1 and has its upper end provided with a cap 4, having therein an opening 5, through which the steam is discharged against the rear wall 6 of the hood or protecting-chamber 7. The chamber 7 has an opening 8 located opposite and on a line with the center of the fan 2. The protecting-chamber 7 is supported on the drain-pipe 9, which is secured in the wall of the cylinder 1 and in the bushing 10. The lower wall of the protecting-chamber 7 is apertured at 11 to permit the condensation from the steam to flow into the drain-pipe 9. The bushing 10 is journaled in the supporting-frame 12. The water dripping through the drain-pipe 9 may be carried away by any suitable conveyer or receptacle, which may be located under the frame 12. The conductor-wires 13 leading to the motor 14 of the fan 45 are made flexible and of sufficient length to permit the cylinder 1 to be turned to any desired position on its bearing in the frame 12. The form of device shown is intended to be used at one end of a room for throwing the 50 moistened air toward the opposite end or toward either side of the room, and is particularly adapted for use in large warehouse-rooms for keeping in storage tobacco and other materials which it is desired to keep

impregnated with a certain amount of moisture, but which would be rotted or otherwise injured if kept in an atmosphere of too high humidity or if subjected to a spray.

The operation of the device is as follows: The flow of steam is controlled by the valve 15 and is permitted to flow through the aperture 5 against the wall 6 of the protecting-chamber 5. The condensation from the pipe 3 will gather in the chamber 7 and be carried away through the drain-pipe 9. The end 16 of the chamber 7 prevents the water from the condensed steam from flowing through that end of the chamber, but permits the steam to pass out into the air-passage or cylinder 1 through the aperture 8. The operation of the fan 2 causes a current of air through the cylinder 1 in the direction of the arrow and helps to draw the steam out of the aperture 8. The action of the fan causes a current of air through the cylinder, which thoroughly mixes with the steam passing out of the protector 7 and blows the mixture a long distance from the apparatus. The amount of moisture with which the air is impregnated will be regulated by the valve 15. The object of having the pipe 3 provided with a cap opening toward the rear is to prevent the steam from being blown directly from the pipe 3 toward the aperture 8, and thus prevents the carrying of spray out of the aperture 8. When the cylinder 1 is turned toward either side, the aperture 5, in the form shown, will discharge toward one of the side walls of the protecting-chamber 7, causing the condensation to flow down such wall and through the aperture 11. The preferred position of the device is that shown in the drawing. If the cylinder is turned in the opposite direction, then the cap 4 may be likewise turned on its threaded seat so as to discharge in a direction away from the discharge of the cylinder 1.

What I claim as my invention, and desire to secure by Letters Patent, is—

1. A humidifying apparatus comprising a passage for the air to be treated, a steam-pipe discharging into said passage, means for forcing the air to be treated through said passage, and a protecting chamber or hood over said steam-pipe, having a steam-opening into said passage but adapted to prevent the drip from the condensed steam from being carried into said passage.

2. A humidifying apparatus comprising a passage for the air to be treated, a steam-pipe discharging into said passage, means for forcing the air to be treated through said passage, and a protecting chamber or hood over said steam-pipe, having a steam-opening into said passage, but adapted to prevent the drip from the condensed steam from being carried into said passage, said steam-pipe being adapted to discharge into said chamber in a direction away from the opening in said protector. 55
3. A humidifying apparatus comprising means for inducing a current of air, a protecting-chamber open in the direction of said current and closed in the opposite direction, and a steam-pipe discharging into said chamber in a direction away from such opening, and a passage independent of said opening for carrying the drip from the condensed steam out of said chamber. 60
4. A humidifying apparatus comprising an outer casing having an opening for receiving air at one end and an opening for discharging air at the other end, an inner casing open toward the discharge end and closed toward the receiving end, a steam-pipe discharging into said inner casing, and means for inducing a current of air through said outer casing. 70
5. A humidifying apparatus comprising an outer casing having an opening for receiving air at one end and an opening for discharging a current of air at the other end, an inner casing open toward the discharge end and closed toward the receiving end, a steam-pipe discharging into said inner casing, a passage, independent of said opening of the inner casing, for carrying the drip from the condensed steam to the outside of the outer casing without contact with said current of air, and means for inducing the current of air through said outer casing. 85
6. In a humidifying apparatus, a supporting-frame, an outer casing journaled thereon and having a receiving-opening and a discharge-opening, an inner casing open in the direction of said discharge-opening and closed in the direction of said receiving-opening, a steam-pipe discharging into the inner casing, and means located in said outer casing for inducing a current of air through the same. 95
7. A humidifying apparatus comprising means for inducing a current of air, a protecting-chamber being open in the direction of such current and closed in the opposite direction, and a steam-pipe extending into said casing and having its inner end terminating free from the walls thereof. 100
8. A humidifying apparatus comprising means for inducing a current of air, a protecting-chamber being open in the direction of such current and closed in the opposite direction, and a steam-pipe extending into said casing and having its inner end terminating free from the walls thereof, and discharging in a direction away from the opening in said casing. 105
9. A humidifying apparatus comprising means for inducing a current of air, a protecting-chamber being open in the direction of such current and closed in the opposite direction, a steam-pipe extending into said casing and having its inner end terminating free from the walls thereof, and means for catching the drip from the condensed steam and preventing the same from being carried into said current of air. 110
10. A humidifying apparatus comprising an outer casing open at opposite ends, means for inducing a current of air through said casing, an inner casing open in the direction of said current of air and closed in the opposite direction, a steam-pipe extending into said inner casing and discharging in a direction away from the opening therein, and means for preventing the drip from the condensed steam from being deposited upon the inside of the walls of the outer casing. 115
11. A humidifying device comprising means for inducing a current of air, a protecting-casing open in the direction of said current and closed in the opposite direction, having its bottom wall sloping downwardly away from said opening, a drip-pipe communicating with said casing for carrying the drip away from said opening and said current, and a steam-pipe discharging into said casing in a direction away from said opening. 120

Signed at Chicago this 15th day of May, 1906.

CHARLES M. COLVIN.
